UNITED STATES PATENT OFFICE.

EDWARD OTTEN, OF BROOKLYN, NEW YORK.

APPARATUS FOR STERILIZING OR COOLING LIQUIDS.

1,190,450.

Specification of Letters Patent.

Patented July 11, 1916.

Application filed February 24, 1915. Serial No. 10,209.

To all whom it may concern:

Be it known that I, EDWARD OTTEN, a citizen of the United States of America, and resident of the borough of Brooklyn, county 5 of Kings, and State of New York, have invented certain new and useful Improvements in Apparatus for Sterilizing or Cooling Liquids, of which the following is a specification.

10 This invention relates to improvements in and relating to apparatus for cooling beer, milk, etc., and sterilizing milk or other such liquids, wherein the flow of the cooling medium is in a direction opposite to the 15 flow of the liquid to be cooled.

An object of the invention is to provide in such an apparatus an increased cooling surface, over which the liquid flows in a constant film, and wherein expensive 20 connections are dispensed with and a comparatively simple and more substantial construction is substituted for the same.

Another object is to provide a cooler in which there are no exposed joints nor sharp 25 corners, wherein sediment may be accumulated, and which may be readily cleaned with an ordinary brush or the like, and kept in a thoroughly sanitary condition.

With these and other objects in view, my 30 invention consists of the novel features, constructions and arrangement of parts, herein-after more fully described and pointed out in the claims.

In the drawings, Figure 1 is a vertical 35 section of my improved apparatus; and Fig. 2 is a side-elevation partly in section.

Similar reference characters indicate corresponding parts throughout the several views.

40 Referring to the drawings, and more particularly to Fig. 1 thereof, two or more cooling sections are provided, each comprising a series of perpendicularly disposed horizontal pipes 1 arranged one below the 45 other in serpentine fashion, and spaced apart by a filling portion 2 secured between each pipe 1, and having concave surfaces, so that there is permitted a continuous and uniform flow of the liquid in a film over the 50 pipes and filling portion. The pipes 1 are secured at each end into casings 3 and 4 which follow the general serpentine outline of the pipes. The said pipes fit into openings or bores 5 in the walls of the casing 55 counterbored so as to provide shoulders 6,

against which the ends of the pipes abut. Inwardly directed surrounding portions 25, inclined to the surface of the pipes, are provided along the said casings, surrounding the said openings 5, and secured to the 60 pipes by means of wipe-joints or solid bronze joints of metallic fillings 26, so that there is provided a continuous cooling surface free from any sharp corners or angles in which sediment might accumulate or become lodged. The said casings are provided also with arched chambers 7 into which the 65 ends of each pair of pipes are fitted and alternating in each of the casings, so that the cooling liquid passing first through the 70 inlet opening 8 and into the pipes is directed from each pipe by means of the chambers into the next higher pipe, and so on to and out of the outlet opening 9 provided at the top of the casing, and preferably, but 75 not necessarily, on the same side of the cooling section as the said inlet opening.

Threaded openings 10 are provided for each of the chambers 7 along the outer surface of the casing, into which plugs 11 are 80 screwed, so that access may be had to any portion of the interior of the apparatus for cleaning the same. The liquid to be cooled is supplied to the surface of the pipes through a trough 12 arranged above the 85 uppermost pipe, having its bottom 13 shaped to conform to the upper portion of the said pipe, and provided adjacent the bottom and at either side thereof with perforations 14 through which the liquid passes 90 on to the surface of the pipes. Projecting downwardly from each of the casings 3 and 4 is a recessed flange 15, which fits and is secured by means of screws 16 to a correspondingly recessed flange 17 projecting upwardly from the casings of the lower set of pipes. When the liquid arrives at the lower 95 end of the upper section, it is conducted along a vertical flange 18 into a trough 19 provided on the uppermost pipe of the lower section, and through perforations 21 therein to the surface of the cooling pipes, from which it is finally conducted to a suitable receiving trough 22. The cooled wort or other liquid is conducted off from the said trough by means of a pipe 23 to the fermenting tanks or other destination in the usual manner. The lower section of the pipes is supported by means of standards 24 secured to 100 the casings thereof, or other suitable means 105 110

might be employed if desired. It is not necessary that I use two cooling sections of pipes, and if desired, I may use only one.

In this construction I have provided a very simple, effectual and sanitary cooling apparatus, in which the liquid is conducted over a very large surface in a comparatively small space, and which, due to the serpentine arrangement of the pipes, flows continuously and with the least amount of resistance, thereby resulting in a more uniformly cooled and cleaner liquid.

I have illustrated and described a preferred and satisfactory form of my invention, but it is obvious that changes may be made therein without departing from the spirit and scope thereof, as defined in the appended claims.

I claim:

1. In a beer cooler, a series of cooling pipes arranged in a serpentine line one below the other, filling strips between the said pipes separating the same from each other and forming a continuous surface therewith, a casing at the ends of said pipes provided with a series of apertures into which the ends of the pipes are secured, shoulders abutting the ends of said pipes, chambers connecting alternately the ends of the cooling pipes, a trough above the uppermost cooling pipe provided with perforations adjacent the said pipe, and a central drip flange at the lower end of the lowermost pipe, adapted to conduct the liquid off of the cooler.

2. In a beer cooler, a series of cooling pipes arranged in a serpentine line one below the other, relatively thin filling strips between the said pipes separating the same from each other and forming a continuous surface therewith, a casing at the end of

Copies of this patent may be obtained for five cents

said pipes provided with a series of apertures into which the ends of the pipes are secured, shoulders abutting the ends of said pipes, inwardly directed portions on said casings surrounding the ends of the said pipes, and inclined toward the surface of the pipes, chambers connecting alternately the ends of the cooling pipes, a trough above the uppermost cooling pipe provided with perforations adjacent the said pipe, and a central drip flange at the lower end of the lowermost pipe, adapted to conduct the liquid off of the cooler.

3. In a beer cooler, a series of cooling pipes arranged in a serpentine line one below the other, relatively thin filling strips substantially square in cross-section between the said pipes separating the same from each other, the exposed surfaces thereof being curved inwardly and forming a continuous surface with the said pipes, a casing at the end of said pipes provided with a series of apertures into which the ends of the pipes are secured, shoulders abutting the ends of said pipes, arcuate chambers connecting alternately the ends of the cooling pipes, a trough above the uppermost cooling pipe provided with perforations adjacent the said pipe, downwardly projecting flanges on said casings provided with recessed portions for securing the same to a lower section of pipes, and a central drip flange at the lower end of the lowermost pipe, for conducting the liquid off of the cooler.

In testimony that I claim the foregoing as my invention, I have signed my name in presence of two subscribing witnesses.

EDWARD OTTEN.
